(57) **CLAIM**

The ornamental design for a handbag, as shown and described.

DESCRIPTION

FIG. 1 is a front perspective view of a handbag showing my new design, with a clasp and D-shaped ring shown in broken lines for the purposes of illustrating environment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of handbag shown in FIG. 1 with shoulder strap, clasp and D rings shown in broken lines for the purposes of illustrating environment.

The broken lines showing the shoulder strap, clasp, and D rings are for the purposes of illustrating environment and form no part of claimed design.

The dashed lines associated with the edges of panels of the handbag, handle, handle's mounts, handle's interwoven applied ribbon, denote stitching and constitute portions of the claimed design.
